UNITED STATES PATENT OFFICE.

HENRY WEBSTER, OF CLINTON TOWNSHIP, VINTON COUNTY, OHIO, ASSIGNOR TO
WEBSTER & KINCAID, OF CINCINNATI, OHIO, A FIRM COMPOSED OF HENRY
WEBSTER AND WILLIAM B. KINCAID.

KILN.

1,295,650.

Specification of Letters Patent. Patented Feb. 25, 1919.

Application filed February 24, 1917. Serial No. 150,778.

To all whom it may concern:

Be it known that I, HENRY WEBSTER, a subject of the King of Great Britain, residing at Clinton township, in the county of 5 Vinton and State of Ohio, have invented certain useful Improvements in Kilns, of which the following is a specification, reference being had therein to the accompanying drawing.

10 The invention relates to kilns, and more particularly to the class of combination brick kilns and driers.

The primary object of the invention is the provision of a kiln of this character 15 wherein a continuous down draft is attained for the proper combustion which travels in a circuitous course through a continuous chamber in which are stacked green bricks for the burning or cooking of the same, the 20 vapor being prevented from condensation and is utilized for the cooking of the bricks, which latter, in the cooking process, emit gas, adding to the products of combustion for the perfect working of the kiln with 25 minimum consumption of fuel.

Another object of the invention is the provision of a kiln of this character wherein the products of combustion will be free from smoke and the vapor or moisture arising 30 from the green bricks will coat with the products of combustion for the burning or cooking of the bricks, and such products of combustion will have a down draft effect so that perpetual and uniform circulation 35 thereof will exist for the drying of the bricks throughout the area of the stacks within the kiln with uniformity.

A further object of the invention is the provision of a kiln of this character wherein 40 the fuel utilized for the firing of the kiln is admitted through the roof of the combustion chamber which is continuous and delivered into the troughs in the bottom of the chamber, whence the firing of the fuel will be 45 more perfectly effected so that the burning of the fuel will take place uniformly and continuously at the bed or base of the combustion chamber and the products of combustion will be retarded by baffles formed by 50 green bricks closely stacked at intervals within the combustion chamber to assure the perfect burning of the bricks and also per-

mitting the stacking of green bricks within the chamber preceding the fire therein during the operation of the kiln.

55 A still further object of the invention is the provision of a kiln wherein the fuel troughs assure the continuous firing of the fuel within the combustion chamber of said kiln.

60 Other objects will be in part obvious and in part hereinafter set forth.

The invention accordingly consists in the features of construction, combination of elements and arrangement of parts which will 65 be exemplified in the construction hereinafter described, and the scope of the application of which will be indicated in the appended claims.

70 In the accompanying drawings:

Figure 1 is a side elevation of a kiln constructed in accordance with the invention, partly broken away;

Fig. 2 is an enlarged vertical transverse 75 sectional view through the kiln;

Fig. 3 is a sectional view on the line 3-3 of Fig. 2;

Fig. 4 is an enlarged vertical fragmentary 80 transverse sectional view, showing one of the draft flues.

Fig. 5 is a fragmentary horizontal sectional view showing in plan a series of the draft flues.

Similar reference characters indicate corresponding parts throughout the several 85 views of the drawings.

Referring to the drawings in detail, A designates generally the body of the kiln which, in this instance, is of rectangular shape, although the same may be of any other shape 90 desirable, and is formed interiorly thereof with a continuous combustion chamber 10, the side runs of which are formed with arched tops 11, while located within the body between the side runs is a main draft flue 12 95 which communicates with a stack or chimney 13 located exteriorly of the body of the kiln A, in this instance at one end thereof, although it may be otherwise located.

100 On the body A of the kiln is a superstructure constituting a fuel shed 14 which is accessible for the delivery of fuel therein in any desirable manner.

Formed in the beds or bottoms of the side

runs of the chamber 11 are spaced longitudinal and transverse grooves 15 and 16, respectively, the outermost of the longitudinal and transverse grooves meeting each other, while 5 the inner longitudinal and transverse grooves intersect one another, and in these grooves is adapted to be received fuel such as powdered coal for the firing of the kiln, the fuel being delivered to the grooves 15 and 10 16 through passages 17 extending vertically through the arched tops 11 of the combustion chamber and opening into the shed 14 through the floor 18 thereof, the fuel within the shed 14 being shoveled over the 15 passages, and such fuel will gravitate therethrough into the grooves 15 and 16 in the bottoms of the side runs of the combustion chamber 10 for the firing of the kiln.

Located within the bottoms of the side 20 runs of the combustion chamber 10 are branch draft flues 19 which open into the main draft flue 12 at their inner ends, while the outer ends thereof are closed, and these branch flues 19 communicate through the 25 medium of ports 20 with certain of the transverse grooves 16 in the bottoms of the side runs of the combustion chamber 10 so as to assure the proper draft within said chamber for the continuous burning of the 30 fuel when fired for the travel of the products of combustion in a circuitous course within the combustion chamber and in one direction therein.

At the point of communication of the 35 branch flues 19 with the main flue 12 are located inverted conical shaped valves 21 which are controlled by operating rods 22 extending into the fuel shed 14 so as to regulate the down draft in the combustion chamber 10 in the operation of the kiln.

Adapted to be arranged at predetermined intervals within the combustion chamber 10, between groups of the longitudinal and transverse grooves 16, are baffle walls 23 45 which are erected from green bricks, and the height of each wall is such as to provide an opening above the top of the wall and between it and the arched top 11 of the combustion chamber 10 so that the products of 50 combustion will travel over the baffle 23 which divides the combustion chamber into compartments 24 for the continued travel of the products of combustion from one compartment to the other in one direction, the 55 direction of passage of the products of combustion being controlled by the down draft which is regulated in the flues 19 by operating the valves 21 controlling the communication of the flues 19 with the main flue 12 of 60 the kiln.

Formed in the side walls of the body A of the kiln are doorways 25 so that access may be had to the combustion chamber 10 for the charging thereof with green bricks and 65 also the removal of the burned bricks

therefrom, the doorways 25 being normally closed in any suitable manner so as to exclude outside air from the kiln.

The passages 17 for the feeding of the fuel from the shed 14 are located for registration with the grooves 15 and 16 which constitute fuel troughs in the bottom of the combustion chamber 10 for the delivering of the fuel into the troughs. The green bricks are stacked within the compartments 70 24 in any desirable manner and on the firing of the fuel at one end of the combustion chamber 10 the products of combustion will be directed in one continuous course 75 circuitously within the kiln, and this course 80 and the down draft interiorly of the kiln is controlled by manipulating the valves 21 which open and close the branch flues 19 leading to the main flue 12, while the baffle walls 23 retard the fire sufficiently long 85 enough to permit the filling of the compartments 24 with green bricks preceding the firing.

The mode of operation of the present invention may be reviewed as follows: When 90 starting a fire in the kiln there would be probably about four chambers set; a paper partition being then placed at the end of the fourth chamber and the setting would continue in the kiln placing a paper partition 95 at the end of every chamber or compartment. The valve 21 at the end of the fourth chamber is now raised to permit smoke and gases from the fire to travel through these communicating chambers from the lighted fire 100 of the first chamber and pass out the intersecting flue 20 through the valve 21 to the main flue 12. The heat in the first chamber passes horizontally through the brick in the adjacent chamber for preheating purposes, 105 etc. As soon as the auxiliary fire in the first chamber has heated the brick therein to the necessary heat to burn slack coal is fed in the openings in the top and forms a gas which travels through the brick in the burning chamber and also the brick immediately 110 in front of the burning chamber pre-heating the brick in the other chambers before passing out through the flue 20 at the fourth chamber. Normally of course the fuel openings or passages in the top of the chambers are closed and are opened at the desired time. During the firing of the first chamber the hot gases arise upwardly being directed 115 by the adjacent vertical partition and pass horizontally through the opening into the adjacent compartment and horizontally over the adjacent compartment and finally pass through the opening or space above the partition 23 which communicates with the third chamber to assure of an even preheating 120 of the bricks. In this connection it is to be understood that the vertical transverse partitions 23 which terminate short of the tops of the side runs prevent the flames and 125 130

products of combustion from passing horizontally from the lower part of one compartment to the lower part of the other compartment and direct the flames upwardly and at the same time permits of these flames and products of combustion to pass horizontally from one compartment to the other on the top thereof. On the other hand, the paper partitions serve to prevent the hot gases, etc., from passing horizontally through the compartments beyond the series of compartments which is being fired and burned. As soon as the operation of the kiln permits the valve 21 in the fourth chamber is closed and the valve 21 in the fifth chamber is raised causing the heated gases and flames to burn out the paper partition between the fourth and fifth chambers and the heat continues to travel through the fifth chamber to preheat the brick therein. This method is continued throughout the entire kiln. Subsequent to the firing of the compartments of the kiln, the doorway 25 will be opened to assure of the cooling of the bricks preparatory to the removal of the same from the kiln. One of the compartments may be opened each day and owing to the draft flue it is apparent that cool air will be drawn through the doorway and through the chamber.

The use of powdered or pulverized coal affords spontaneous or quick combustion on the firing thereof and the firing will be continuous in the grooves 15 and 16 in the bottom of the combustion chamber 10 within the kiln so that the green bricks will be thoroughly dried in a uniform manner and expeditiously without maximum consumption of fuel, thereby rendering the kiln economical in the use of fuel and by reason of its particular construction assuring the thorough burning or curing of the bricks efficiently.

From the foregoing description, taken in

connection with the accompanying drawings, the construction and operation of the herein described kiln will be readily apparent and, therefore, a more extended explanation has been omitted.

Having thus described my invention, I claim:

1. In a brick kiln, a body having a continuous chamber provided with a series of communicating compartments, a main draft flue located between the side runs of the chamber, branch flues communicating with the main flue and extending beneath the bottom of each compartment in the chamber, the bottoms of each compartment being formed with longitudinally and transversely extending intersecting grooves which act as fuel receiving troughs, said bottoms also having ports opening into the branch flue and valves for controlling the communication between the branch flues and the main flue. 65

2. In a brick kiln, a body having a continuous chamber provided with communicating compartments, a main draft flue located between the side runs of the chamber, branch flues communicating with the main flue and extending beneath the bottom of each compartment in the chamber, the bottom of each chamber being formed on its upper surface with longitudinally and transversely arranged intersecting grooves which 75 act as fuel receiving troughs, said bottoms also having ports therein opening into the branch flues, a fuel shed above the body, said body being formed with openings communicating with the fuel shed and register 80 ing with the grooves in the bottoms of each compartment of the chamber, valves controlling communication between the branch flues and the main flue and valve rods operable from within the shed for actuating the 85 valves.

In testimony whereof I affix my signature.

HENRY WEBSTER.
